(57) CLAIM

The ornamental design for a decorative subceiling panel unit, as shown and described.

DESCRIPTION

FIG. 1 is a bottom perspective view of a decorative subceiling panel unit showing my new design, in a concave configuration;

FIG. 2 is a top perspective thereof;

FIG. 3 is a top plan thereof;

FIG. 4 is a bottom plan thereof;

FIG. 5 is a sectional elevational view thereof taken along the line 5—5 in FIG. 3;

FIG. 6 is a sectional elevational view thereof taken along the line 8—8 in FIG. 4;

FIG. 7 is a bottom perspective view of a decorative subceiling panel unit showing my new design, in a convex configuration;

FIG. 8 is a top perspective thereof;

FIG. 9 is a top plan thereof;

FIG. 10 is a bottom plan thereof;

FIG. 11 is a sectional elevational view thereof taken along the line 5—5 in FIG. 9; and,

FIG. 12 is a sectional elevational view thereof taken along the line 6—6 in FIG. 10.

The substantially square cell areas of the design such as shown in FIG. 1 are opaque. One configuration is concave with respect to the ceiling, as shown in FIG. 1. A second configuration is convex with respect to the ceiling, as shown in FIG. 7.
